UNITED STATES PATENT OFFICE.

PETER P. FIGUEROA, OF NEW YORK, N. Y.

CUSPIDOR.

1,315,221.

Specification of Letters Patent. Patented Sept. 9, 1919.

Application filed October 5, 1916. Serial No. 123,871.

To all whom it may concern:

Be it known that I, PETER P. FIGUEROA, a citizen of the United States, and resident of New York, in the county of New York and State of New York, have invented certain new and useful Improvements in Cuspidors, of which the following is a specification.

This invention relates to cuspidors and its object is to provide the same for public use and to be mounted on a pedestal or under the top of a counter, desk or chair seat and normally under cover but which may be drawn or swung out for use and will return to its proper location when released and at the same time to rotate or move advertising signs or pictures grouped about the device for ornamentation or utility. These and other details and objects of the invention will be more fully described in the following specification, set forth in the claims and illustrated in the accompanying drawings, wherein;

Figure 1, is a front elevation of the device.

Fig. 2, is a horizontal sectional view above the cuspidor drawer.

Fig. 3 is a detail view of the disinfecting spray.

Fig. 4 is a vertical sectional view of the cuspidor and its drawer.

Ordinarily cuspidors are located on floors and at some distance from the user and in consequence they often fail in their purpose and the floor in their vicinity soon becomes filthy. Another deficiency in the ordinary cuspidor is the lack of means for destroying or preventing the increase of disease germs and the elimination of odors.

The present invention is designed to overcome these objectionable features and at the same time to provide an ornamental and useful stand to not only contain the cuspidor, but exhibiting in its various sides and displaying pictures, advertisements or pockets containing circulars, cards or time tables.

The whole may be surmounted by a gas jet or a figure carrying the same.

In the various views of the cuspidor 5, it is shown as being made of sheet metal and is a tray of sufficient depth for the purpose and located in a drawer 6 having a hinged front 7 to permit the ready removal of the cuspidor and a rear compartment 9 in which may be located the spraying solution and the devices for delivering the same into the

cuspidor 5 with each retraction of the drawer to eliminate the odors or destroy the injurious germs therein.

In Figs. 2 and 3 will be seen a small tank 9 to contain a disinfecting liquid and connected with one side of the tank is a cylinder 10 having a piston 11 just about to close the inlet 12 when the drawer is open but permitting the liquid to fill the lower end of the cylinder. When the drawer with the cuspidor closes it strikes the head 13 of the stem 14 and forces the piston inward, closing the inlet and forcing a small amount of the liquid out of the nozzle 15 and spraying the contents of the cuspidor.

The drawer 6 when pulled out unwinds the strap 16 from the spring drum 17 and consequently when the drawer is released it automatically returns to the casing 18, a pull 6' being provided to manipulate the drawer.

The casing 18 is supported by the upright 19 and base 20 while on its top is an upright 21 carrying a frame 25, preferably polygonal and having panels 26 on its sides and sloping panels 27 at its upper end. At the outer end of sleeve 22 may be located some ornamental figure 28 carrying a gas jet 29 for lighting cigars and depending from the casing 18 may be panels 30 for signs or pictures, or they may be boxes to contain cards, hand bills, time tables, etc.

It is obvious that this invention is susceptible of other modified forms to satisfy special wants and locations and that they may be adopted without departing from the essential features above described or from the scope of the appended claims.

The device may be mounted on an ornamental pedestal and placed at some convenient spot where cuspidors are needed and the panels around the revolving frame filled with pictures, mirrors or advertisements. The figure at the top of the device may be either for a light or a water jet, or may also carry an advertisement.

The casing may also be secured to a wall or a counter and the pivoted cuspidor may be secured beneath the side of a bed, chair or other furniture. It is evident that the spraying device may be supplied with water to flush the pan if found desirable.

What I claim as new is:

1. In a cuspidor, the combination of a pedestal, a housing at the top of same, a drawer in the housing, means for returning

the drawer to the housing, a cuspidor in the drawer, a tank for a disinfectant, a spray pipe for the latter, a pump, and means for actuating the pump when the drawer is closed to spray the cuspidor.

2. In a cuspidor, the combination of a pedestal, a box thereon with a rear chamber, a drawer, a spring in the chamber and adapted to retract the drawer, a reservoir

for a disinfectant, a pump communicating 10 with the same, a spray pipe, and a plunger adapted to be operated by the retracted drawer to discharge the disinfectant from the spray pipe into the drawer.

Signed at New York, in the county of New 15 York and State of New York this 23 day of September, A. D. 1916.

PETER P. FIGUEROA.
